UNITED STATES PATENT OFFICE.

WALTER E. ROE, OF MISHAWAKA, INDIANA, ASSIGNOR TO DODGE MANUFACTURING COMPANY, OF MISHAWAKA, INDIANA, A CORPORATION OF INDIANA.

AUTOMATIC LUBRICATOR.

1,295,926.

Specification of Letters Patent.

Patented Mar. 4, 1919.

Original application filed January 18, 1915, Serial No. 2,891. Divided and this application filed September 16, 1918. Serial No. 254,274.

To all whom it may concern:

Be it known that I, WALTER E. ROE, citizen of the United States, residing at Mishawaka, in the county of St. Joseph and State 5 of Indiana, have invented certain new and useful Improvements in Automatic Lubricators, of which the following is a specification.

My invention relates to improvements in 10 automatic lubricators and it consists more especially of the features set forth in the annexed claims.

The purpose of my invention is to provide 15 an automatic lubricator applicable to stationary shafts, axles, etc., or to those that are rotated; that supplies various types of stationary collectors adapted to lubricate any type of adjacent bearing; that uses oil lifters to coöperate with the collectors; and 20 that also uses centrifugal force for raising the oil to the collectors.

With these and other ends in view I illustrate in the accompanying drawings such instances of adaptation as will disclose the 25 basic features without limiting myself to the specific details shown.

Fig. 1 is a side elevation of a lubricator applied to a rotating shaft.

Fig. 2 is an end elevation partly in section 30 of Fig. 1.

Fig. 3 is an end elevation similar to Fig. 2 showing the point of oil delivery to a collector having upper delivery openings.

Fig. 4 is a transverse section of a collector having a bottom delivery opening.

Fig. 5 is a side elevation of a lubricator applied to a stationary axle.

Fig. 6 is an elevation partly in section of Fig. 5.

Fig. 7 is a plan view of a detached collector, partly in section on line $\alpha\alpha$ of Fig. 6.

Fig. 8 is a side elevation of the arm portion of a detached collector, in section on yy of Fig. 6.

Fig. 9 is a diagrammatic representation 45 of three distinct lubrication adaptations at A on a pulley placed adjacent a hanger; at B adjacent a clutch; and at C adjoining a tight pulley on a line shaft.

In carrying my invention into practice 50 I may use the specific adaptations shown in the accompanying drawings or any practical alternatives, or equivalents thereof when the features involve the automatic ap-

plication of lubricant the bearing surfaces 55 in a positive self contained manner, whether the one or the other the bearing or the shaft or axle are the movable elements. It is immaterial how the lubricant is raised to a delivery position whether by fins, vanes or 60 by centrifugal force.

Ring oilers have been commonly used to 65 elevate lubricant, as instanced in my co-pending application Serial #2891 of Jan. 18, 1915 of which this is a divisional, but in 70 practice the oil carried in a rotating chamber will be distributed around the inner surface of the casing at certain speeds by centrifugal force so that a ring oiler resting on the shaft could not elevate any oil because of no longer being in contact with it. The purpose of this improvement is to break up such a layer of moving oil and deliver it to a relatively stationary collector 75 having a "hopper" to gather the oil and deliver it to adjacent bearing surfaces.

When ring oilers are used with rotating 80 shafts and non-rotating lubricating casings the previously mentioned difficulty does not manifest itself, but since this type of bearing is limited in practical use other provisions must be made to meet different conditions. This has been done in the present exemplification wherein a shaft 1 supports a rotating lubricant container 2 which may 85 be a part of a revolving wheel rotating on a stationary shaft between collars 11 or the shaft 1 may revolve in an adjacent bearing Fig. 9 A in which case the container 2 would be secured to the shaft in any suitable manner, the oil grooves 26 directing oil to the bearing 50. In the former case these grooves supply oil directly to the bearing faces of hub 3 and shaft 1. The specific showing in Fig. 1 is not to be construed in 90 any limited sense whatever as the application of movable oil raising means to relatively stationary collectors is claimed in its broadest sense regardless of the specific details or functions used to accomplish the 95 raising of the lubricant for delivery to the collector and the direction therefrom by gravity to the point where lubrication is required.

In Fig. 9 different uses are diagrammatically shown at A the lubricant of a bearing wherein the container 2 may be combined with a pulley that is driven by shaft 100

1. In Fig. 9 B it serves a clutch 51 and in Fig. 9 C it is used as a loose pulley in connection with a tight pulley 52.

The container 2 has a hub 3 which supports an enlarged bell shaped casing that incloses oil chamber 4. A filling plug 5 is placed in the casing wherever desired. The casing 2 has a threaded opening 10 into which a follower ring 6 passes to close the open end. This opening is made large enough to admit of the passage of collectors 17 and 18 in assembling. The ring 6 has spanner holes 7 around its rim by means of which it can readily be placed in the casing or when necessary removed therefrom. It is also supplied with an internal packing 8 next to the shaft 1 and an external packing washer 9. When so assembled on the shaft a completely inclosed lubricator is provided. As instanced in Fig. 1 two collars 11 prevent endwise movement on the shaft. These are held by set screws 12.

The oil lifting means may be paddles 16, Fig. 4, or a single fin Figs. 2 and 3 or centrifugal motion Fig. 6. In either case a stationary collector 17, 18 or 40 will receive the lifted oil as exemplified in Figs. 3 and 6 and deliver it to oil grooves 26, 47 or any others that may be provided. When a single fin 13 is used its sides may be curved at 14 to more readily hold a lubricant regardless of the direction the container 2 may rotate. The lubricant level, when the parts are all at rest, is shown approximately at 15. The paddles 16 may be used with collector 17 and the fin 13 with collector 18, or either collector with the centrifugal lift of Fig. 6. In the latter case the radial collector walls 19 and 20 and the curving side walls 21 would terminate 40 near the inner face of the lubricant chamber 4, similar to the finger 43 shown in Fig. 6.

The oil collectors, 17, 18 and 40 direct the oil by gravity to the point where it is required. Collectors 17 and 18 hang loosely 45 on the shaft 1. Both have a weighted bottom portion 23 which serves to keep the upper part inclosed by walls 19, 20 and 21 uppermost. Collector 40 is held in its best collecting relation by a set screw 41 on stationary axle 29. The oil collected by 17 is delivered near the upper face of the shaft 1 through openings 22 formed in one or both walls 21 as the exigencies of practice may demand; that gathered by collector 18 passes 55 along an inner groove 24 to a lower outlet 25 opening toward either or both faces. The collector 40 with its radial arm 43 Fig. 6 gathers the oil by means of its curved side edges 45 Fig. 7 formed on each side of the center web 44. Collecting grooves 46 carry the oil toward the surface of the shaft delivering it to grooves 47 or 26 as the case may be. The oil delivery of Fig. 3 is shown at 27, that of Fig. 4 at 28, and that of Fig. 6 65 at 48. In the latter case any surplus oil fol-

lows the hub of 40 approximately as at 49 to return to the oil supply 35 in the bottom of a container 32 Figs. 5 and 6. These several parts may be used in interchangeable adaptations according to the various demands of 70 different lubricating conditions without departing from the broad scope of the invention.

When lubricating a stationary axle as 29, Figs. 5 and 6 another expedient may be used. In such an adaptation the oil collector 32 may be a part of a wheel hub 31 that has bearing against a shoulder 30. An inclosed oil chamber 34 is formed inside of the collector, to this a filling plug 36 affords access 80 for lubricant. In order that the collector 40 may be assembled on the end of axle 29 where it is followed by a nut 39 a large threaded opening 33 similar to opening 10, Fig. 1 is provided. This is closed by a cap 85 37 having a hexagonal or other shaped nut on the outside at 42. A packing ring 38 is placed between the cap 37 and the casing 32. The relative dimensions of the opening 33, collector 40 and axle 29 are such as to permit of the assembling of 40 on the end of axle 29 without interference even with the hub 3, full against the shoulder 30, or as shown when the collector is inserted through opening 33 before the outer end of axle 29 95 projects too far from hub 31 within the chamber 34.

It is a well known expedient to, under certain conditions, form oil grooves in the shaft instead of in a hub supported thereby but 100 such an adaptation could only be construed as using a substantial equivalent of the disclosure made herein.

It will be observed that an automatic lubricator is provided which is adaptable to the 105 varying conditions found in practical engineering without the use of complex intricate and expensive moving parts. A lubricator that can be even radically modified by designing engineers without departing from 110 the spirit of my invention.

What I claim is:

1. A moving member having a bearing surface, a shaft therein, an oil lifter forming a part of and actuated by said member, and an oil collector adapted to deliver lubricant from the lifter to the bearing surface. 115

2. An axle or shaft, a hub rotatable thereon, an oil chamber combined with said hub, means for automatically raising oil in the 120 chamber through a rotation thereof, an oil collector relatively stationary with respect to the moving member, oil directing grooves formed in the bearing surfaces, suitable directing means comprised in the collector 125 adapted to divert oil therefrom to the points where lubrication is desired, and means for inclosing the collector within the chamber.

3. A movable member having a bearing surface, a support therefor, a lubricant 130

holder combined with such member, means confined within the chamber for automatically raising the lubricant to a higher level through the movement of said member, and 5 means for collecting the lubricant and diverting it to points where lubrication is required.

4. A self lubricating bearing, comprising a shaft or axle, a rotatable member thereon 10 having coöperative relation thereto, oil bearing surface, an oil lifting device combined with the said member and a collector placed adjacent the path of travel of the 15 lifting device adapted to receive the lifted oil and deliver the same to grooves aforesaid.

5. In lubricating system, a rotatable member, a stationary member coöperating therewith, a lubricant chamber formed in the moving member, a collector supported by the stationary member inclosed within the moving member adapted to receive lubricant raised through the rotation of the rotatable member, and means for directing the collected lubricant to points adjacent thereto where lubrication is required.

6. In lubricating systems, a rotatable member combined with a lubricant container both adapted to rotate together, a relatively stationary member placed within the container, a support for both, means for raising lubricant through the rotation of the container, and means for collecting such raised lubricant by the stationary member for further distribution to the bearing parts on

which the rotatable member depends for its support.

7. In lubricating systems, a rotatable member having a lubricant container combined therewith, a relatively stationary lubricant collecting member placed within the container, a support common to both the rotating and stationary members, and means for delivering lubricant to the stationary 40 member through the movement of the rotatable member.

8. In lubricating systems, a rotatable lubricant container, a relatively stationary lubricant collector wholly inclosed by the container, means for supporting both on separate planes adjacent each other, and means adapted to supply lubricant to the collector through a movement of the container.

9. In lubricating systems, a bearing member, a rotatable lubricant container, a stationary collecting member therein, and means adapted to continuously supply lubricant to the collector through the movement of the container for delivery to the bearing 60 member.

10. In automatic lubricators, a bearing part, a rotatable lubricant container, and a relatively stationary collector supplied with lubricant by the latter for delivery to the former.

In testimony whereof I affix my signature in the presence of two witnesses.
